(57) CLAIM

The ornamental design for a pet food dish, as shown and described.

DESCRIPTION

FIG. 1 is a front, top, left, perspective view of a pet food dish in accordance with our design;

FIG. 2 is a top, plan view thereof;

FIG. 3 is a bottom, plan view thereof;

FIG. 4 is a back, perspective elevation view thereof;

FIG. 5 is a right side, perspective elevation view thereof;

FIG. 6 is a back, bottom perspective view thereof;

FIG. 7 is a cross-section taken along line 7-7 of FIG. 2;

FIG. 8 is a front, top, perspective view of the pet food dish in accordance with our design; and,

FIG. 9 is a front, top, perspective view of the pet food dish in use.

The broken lines illustrate portions of the environment of the pet food dish which form no part of the claimed design.

The dash-dash lines in FIG. 2 show the boundary of the cross-section illustrated in FIG. 7.

1 Claim, 9 Drawing Sheets

FIG. 3

FIG.4

FIG. 5

FIG. 6

FIG. 8

FIG. 9
